[57] CLAIM

The ornamental design for an electrical control box, as shown and described.

DESCRIPTION

FIG. 1 is a front and upper left perspective view of an electrical control box showing my new design;

FIG. 2 is a left side elevation view of an electrical control box shown on an enlarged scale;

FIG. 3 is a front elevation view thereof;

FIG. 4 is a right side elevation view thereof;

FIG. 5 is a top plan view thereof;

FIG. 6 is a rear elevation view thereof;

FIG. 7 is a bottom plan view thereof; and,

FIG. 8 is a front elevation view of an electrical control box showing a second embodiment of my new design. The rear and side elevation views of the second embodiment are the same as those of the first embodiment, and the top and bottom plan views of the second embodiment are mirror images of those in the first embodiment.
